UNITED STATES PATENT OFFICE.

ROBERT E. INGAL, OF CHICAGO, ILLINOIS.

RADIATOR ATTACHMENT.

1,241,389.

Specification of Letters Patent. Patented Sept. 25, 1917.

Application filed October 15, 1915. Serial No. 56,112.

To all whom it may concern:

Be it known that I, ROBERT E. INGAL, a citizen of the United States, and a resident of the city of Chicago, county of Cook, and State of Illinois, have invented certain new and useful Improvements in Radiator Attachments, of which the following is a specification.

My invention relates to improvements in 10 radiator attachments, and has for its object the provision of a construction of this character adapted to be positioned on an ordinary steam or hot water radiator to improve the quality of the air circulating thereover.

15 The invention consists in the combinations and arrangements of parts hereinafter described and claimed.

The invention will be best understood by 20 reference to the accompanying drawings forming a part of this specification, and in which—

Figure 1 is a top plan view, with portions removed and others broken away, of an attachment embodying my invention,

25 Fig. 2, a longitudinal section of the same shown in position of use, and taken on line 2—2 of Fig. 1,

Fig. 3, a similar section taken on line 3—3 of Fig. 1,

30 Fig. 4, a transverse section of the attachment, and

Fig. 5, a rear elevation of the same.

The preferred form of construction, as 35 illustrated in the drawings, comprises a rectangular vessel 6 having a water pan 7 formed along one side thereof, the other side of said vessel being provided with an opening 8 traversed by a reinforcing bar 9. A screen 10 is arranged in opening 8 and is 40 supported on bar 9 and lugs 11, as indicated. The vessel 6 is provided with an opening 12 in the side opposite the opening 8, this opening 12 being also covered by a screen 13. The vessel 6 is provided with a removable

45 cover 14 and with depending flanges or aprons 15 around its lower edges adapted to fit over the sides and ends of an ordinary radiator 16 and maintain the vessel in position on said radiator. A depending guard 50 or apron 17 is attached to the rear side of vessel 6 and is adapted to fit between the

radiator 16 and an adjoining wall 18, said guard serving to protect the wall and to insure against over-tipping of the vessel.

In use the pan 7 is supplied with a suitable 55 quantity of water and the vessel is positioned on top of the radiator with the guard 17 interposed between the radiator and the adjoining wall in which position the opening 12 is in the outer side of the vessel. By 60 this arrangement, the upwardly flowing air heated by the radiator 16 will pass upwardly through the opening 8 over the water in pan 7 and out through the opening 12, thus absorbing a suitable quantity of moisture for 65 breathing purposes. The combined action of the screens 10 and 13, and the water in the pan 7 serve to eliminate dust from the air.

While I have illustrated and described the 70 preferred form of construction for carrying my invention into effect, this is capable of variation and modification without departing from the spirit of the invention. I, therefore, do not wish to be limited to the 75 precise details of construction set forth, but desire to avail myself of such variations and modifications as come within the scope of the appended claims.

Having described my invention what I 80 claim as new and desire to secure by Letters Patent is:

1. A device of the class described comprising a vessel arranged to be positioned on top of a radiator, there being an opening in 85 the bottom of said vessel extending along one side thereof; a water pan occupying the other side of the bottom of said vessel; a reinforcing and supporting bar traversing said opening; a screen arranged over said 90 opening and resting on said bar; and a screened opening in the side of said vessel above said water pan opposite the opening in the bottom thereof, substantially as described.

2. A device of the class described comprising a vessel arranged to be positioned on top of a radiator, there being an opening in the bottom of said vessel extending along one side thereof; a water pan occupying the 100 other side of the bottom of said vessel; a reinforcing and supporting bar traversing

said opening; a screen arranged over said opening and resting on said bar; a screened opening in the side of said vessel above said water pan opposite the opening in the bottom thereof; and a depending apron on said vessel on the side opposite said screened opening, substantially as described.

In testimony whereof I have signed my name to this specification in the presence of two subscribing witnesses.

ROBERT E. INGAL.
